UNITED STATES PATENT OFFICE.

JOHN ROGERS, OF NEW CANAAN, CONNECTICUT.

DESIGN FOR A GROUP OF STATUARY.

Specification forming part of Design No. 11,183, dated May 6, 1879; application filed April 9, 1879.
[Term of patent 14 years.]

To all whom it may concern:

Be it known that I, JOHN ROGERS, of New Canaan, in the county of Fairfield and State of Connecticut, have originated and designed a Group of Statuary, of which the following is a full, clear, and exact description, reference being had to the accompanying photographic illustration, making part of this specification.

The group is called "Polo," and represents two men on horseback playing this game. The one most in the background has reined in his horse, and with his mallet in his right hand is trying to push the ball on the ground past the flag-staff, which can be seen close by his horse's head. The horseman in the foreground is passing the other at full gallop, and, with his mallet also against the ball, is trying to take it away from the first one in an opposite direction. The men are dressed in close-fitting caps and shirts with short sleeves, breeches, and high boots, and have handkerchiefs around their necks, as shown by the one in the foreground.

What I claim as my invention is—

A design for a group of statuary representing two men on horseback playing a game of polo, in which one man is trying to take the ball with his mallet past the flag-staff, while the other one passes him at full gallop, and tries to prevent him by forcing the ball in an opposite direction, substantially as shown in the accompanying illustration.
